UNITED STATES PATENT OFFICE.

FERDINAND KRONENBERGER, OF NEW YORK, N. Y.

PAPER LOCK.

Application filed August 22, 1921. Serial No. 494,316.

To all whom it may concern:

Be it known that I, FERDINAND KRONENBERGER, a citizen of the United States, and resident of the city of New York, in the county of Queens and State of New York, have invented certain new and useful Improvements in Paper Locks, of which the following is a specification.

This invention relates to closures for paper boxes and is especially applicable to sealing flaps.

One of the objects of this invention is the provision of a simple paper lock which is formed entirely from the parts of the box or envelop and which automatically snaps into place on the completion of the locking movement.

A further object of this invention is the provision of means for quickly and easily fastening a flap into place, in which means the parts cannot be separated unless they are destroyed.

A further object of this invention is the provision of a box closure which, while acting as an effective seal, dispenses with the necessity for adhesives or extraneous fastenings.

A still further object of this invention is the provision of a box closure in which side-wise manipulation of the parts is prevented.

Other objects will appear as the description progresses. In the drawings accompanying this specification, Fig. 1 is a front view of my improved lock. Fig. 2 is a vertical section of the same on the line 2—2 of Fig. 1. Fig. 3 is a front view of the tab member and Fig. 4 is a similar view of the receiving or slotted member. Fig. 5 is a front view of a modified form of my invention. Fig. 6 is a vertical section of the same on the line 6—6 of Fig. 5. Fig. 7 is a front view of the slotted member of the lock shown in Fig. 5. Fig. 8 is a similar view of the tab member. Fig. 9 is a front view of a box blank to which my improved lock has been applied. Fig. 10 is a perspective view of a box made from the blank, and Fig. 11 is a similar view of a similar box in which the lock shown in Fig. 5 is used.

It will be seen that two types of my improved lock are shown in the drawings. In one type, the movable member, that is, the flap to be locked, is partly slotted and formed substantially into a tab, and the receiving member or stationary box part into which the tab is inserted, is slotted suffi-

ciently to receive the entire tab throughout the width thereof, inclusive of the slotted portion. In the other type of my lock, the movable flap is slotted by means of a transverse cut to receive a tab cut by means of suitably disposed slits in one of the stationary sides of the box. Both types of my improved lock, however, are of substantially the same construction, and the same numerals will therefore be used to designate similar parts on each.

The tab portion 10 of the lock is preferably rounded or bevelled at the free extremity thereof for easy insertion into a suitable slit, and has cut therein a pair of slits 11 extending inwardly from the edges of the tab toward each other for any desired distance. The slit 13 into which the tab 10 is to be inserted, is made by a suitable cut in the paper and is of substantially the same length as the distance between the outer extremities of the slits 11, and, of course, is of less length than the width of the member in which it is cut. It will be seen that shoulders as 14 are formed on one side of the slits 11, while the shoulders 15 are formed on the other side thereof.

In order to lock the parts together, the tab 10 is pushed into the slit 13 until the shoulder portions 15 have passed completely through the said slit 13, whereupon the parts become firmly locked together and cannot be withdrawn without damage thereto, as will now be explained in detail. On the insertion of the tab 10 into the slit 13 of the receiving member 16, that portion 17 of the receiving member on one side of the said slit 13 and outside of the inserted tab 10 is sprung outwardly from the original plane 85 of the paper surface, while that portion 18 on the other side of the slit 13 is simultaneously sprung inwardly from the plane of the paper surface. The tendency of the outwardly sprung portion 17 to resume its original flat position, results in pressure inwardly on the entering portion of the tab 10 and tends to press the shoulders 15 inwardly, the extremities of said shoulders being free to move when unsupported, by reason of the separating slits 11. The inwardly sprung portion 18 similarly tends to straighten out into its original position and therefore transmits the outward pressure on to the shoulders 14 of the tab 10.

From the above it will be clear that during the operation of inserting the tab into

the slit provided therefor, the shoulders 15 are pressed inwardly, while the shoulders 14 are pressed outwardly or in the opposite direction, whereby said shoulders tend to become separated in the direction of the paper thickness.

At the moment, however, that the insertion of the shoulders 15 through the slit 13 is completed, said shoulders being no longer supported by the portion 18 of the receiving member, automatically snap inwardly, while the said portion 18 tends to straighten out in an outward direction and hence comes into close contact with the inner surface of the shoulders 14. The lateral movement of the shoulders 15, and of the portion 18, though slight, is sufficient to bring the free extremities of said shoulders into contact with the edge of the portion 18, so that the edges of said shoulders and said portion abut one against the other for a substantial part of each edge, and lie approximately in the same plane. Any attempt now to withdraw the tab 10 from the slit 13, is resisted by the abutting edges of the shoulders 15 and the portion 18, whereby the parts cannot be separated without tearing said shoulders or said portion 18. Similarly, the slotted edges of the shoulders 14 are pressed outwardly and contact with and abut against the slotted edge 17, whereby further insertive movement of the parts is prevented. It will be noted that, in distinction from the usual tab and slit lock, no paper is cut away at the shoulders 14 and 15, but that dependence is placed on the spring action of said shoulders, as has been pointed out above.

In that form of my lock shown in Figs. 5, 6, 7, 8 and 11, the slit 13 is cut in the movable member such as a box flap 16, while a stationary part of the box such as the receiving member 19 or the box front 20 has the tab member 10 cut therein, as by means of the side cuts 12', whereby the lock is reversed in position, while the operation thereof remains exactly the same as in the other type. Said side cuts 12' are made of sufficient length to allow the passage thereunder of the movable flap to a point at which the locking operation above described can take place.

In the application of my improved lock to a box such as the egg carton 21, means are provided for maintaining the lock parts in the locked position thereof, whereby the unlocking of the said parts by sidewise manipulation is prevented. In addition to providing a double lock 23, I provide a preferably corrugated reinforcing flap 24 folded under and secured to the under side of the box cover 25, the edges 26 of said flap being bevelled at an angle of 45 degrees, as shown in the blank 27 (Fig. 9), and a second flap 28 integral with the box front and bent approximately at right angles thereto, said

flap 28 being bevelled at the edges 29 thereof, similarly to the edges 26. When the lock is fastened in place, each of the edges 26 comes into contact with and abuts against the adjacent edge 29, since the flaps 24 and 28 lie substantially in the same plane. It will therefore be seen that movement of the cover 25 relatively to the box body in a sidewise direction is prevented, whereby the lock is maintained in its locked position, and the box is effectively sealed without the use of adhesives or other extraneous fastenings of metal or other material.

I claim:

1. A closure comprising a flap having slits severing the material of said flap and directed inwardly from the edges thereof, and a receiving member having a slit cut therein substantially equal in length to the width of said flap at the slotted part thereof.

2. A closure comprising a partly slotted member comprising a tongue portion and a body portion immediately adjacent to and severed from said tongue portion, and a second member slotted to receive said first mentioned member in such a manner that the edge of the slit in the first member contacts with a slotted edge in said second member.

3. A closure comprising a tab having slit-formed shoulders and a body portion severed from and at least as wide as said tab, and a slotted receiving member, said tab being adapted to be inserted in the slit of said receiving member to a point where said shoulders of said tab member abut against the slotted edge of said receiving member whereby relative movement of said flap and said receiving member is prevented.

4. A closure comprising a flap, bendable shoulder portions formed by slits severing the material of said flap and directed inwardly toward each other from the edges of said flap, and a receiving member having a slit cut therein parallel to the slits in said flap and of sufficient length to receive said flap together with the slit formed shoulder portions thereof, said flap being adapted to be inserted into the slit of said receiving member for a sufficient distance to allow the edges of the shoulder portions of said flap and the edges of the slit in said receiving member to automatically snap into abutting relation.

5. In a box, the combination of a box front member, a lip on the upper edge of said front member integral with and bent from said front member substantially at right angles thereto, bevelled ends on said lip, a cover member, a reinforcing flap gummed to the under side of said cover, bevelled ends on said reinforcing flap, a partly slotted locking flap on one of said members, and slit-formed edges equal in

length to the width of said flap at the slits thereon on the other of said members, said flap being adapted to enter between said slit-formed edges for locking said flap, and 5 the adjacent bevelled corners of said lip and said reinforcing flap being adapted to engage for maintaining said flap in the locked position thereof.

6. In a box, the combination with a box 10 front and a movable flap, of means for locking said flap to said front and means for locking said flap against sidewise movement of the locking means comprising a lip integral with and bent from said 15 front, bevelled ends on said lip, a reinforcing flap secured to the under side of said movable flap, and bevelled ends on said reinforcing flap adapted to engage the bevelled ends on said lip, in the locked position of said movable flap.

7. In a box, a tab having slit-formed edges extending inwardly toward each other and a body portion severed from said tab by said slits and at least as wide as said 25 tab, a tab receiving member having slit-formed edges adapted to engage the slit formed edges of said tab, and means on said

box for preventing sidewise movement of said slit-formed edges.

8. A paper lock comprising a tab, a 30 slitted member adapted to receive said tab, and shoulders on said tab free at one extremity thereof and adapted to automatically snap into abutting edge contact with said slitted member on the completion of 35 the insertive movement of said tab into the slit of said slitted member, a body portion substantially wider than said tab and partly severed from said tab, and shoulders on said body portion immediately adjacent to 40 and of the same length as the shoulders on said tab.

9. A paper lock comprising a slitted receiving member, a second member, a tab formed from the body of said second member by means of severing cuts therein, and severing slits in said tab directed inwardly 45 toward each other from the tab forming cuts.

Signed at New York, in the county of 50 New York and State of New York, this 19th day of August, A. D. 1921.

FERDINAND KRONENBERGER.
